DESIGN FOR A DRINKING VESSEL FOR ANIMALS OR THE LIKE

Stanton E. Werner, Highland Park, N. J., assignor to E. R. Squibb & Sons, New York, N. Y., a corporation of New York

Application October 22, 1937, Serial No. 72,371

Term of patent 3½ years

To all whom it may concern:

Be it known that I, Stanton E. Werner, a citizen of the United States, residing at Highland Park, in the county of Middlesex and State of New Jersey, have invented a new, original, and ornamental Design for a Drinking Vessel for Animals or the like, of which the following is a specification, reference being had to the accompanying drawing, forming part thereof.

In the drawing:

Fig. 1 is a perspective view of a drinking vessel for animals, or the like, embodying my new design; and

Fig. 2 is a longitudinal vertical axial section thereof.

I claim:

The ornamental design for a drinking vessel for animals or the like, substantially as shown.

STANTON E. WERNER.
